UNITED STATES PATENT OFFICE.

RICHARD M. DAY, OF HUDSON, SOUTH DAKOTA.

INTERNAL-COMBUSTION ENGINE.

1,247,378.

Specification of Letters Patent.

Patented Nov. 20, 1917.

Application filed October 26, 1915. Serial No. 56,091.

To all whom it may concern:

Be it known that I, RICHARD M. DAY, a citizen of the United States of America, residing at Hudson, in the county of Lincoln 5 and State of South Dakota, have invented certain new and useful Improvements in Internal-Combustion Engines, of which the following is a specification, reference being had therein to the accompanying drawing.

10 This invention relates to internal combustion engines and has for its object the production of a simple and efficient means for actuating the control valves for regulating the inlet and exhaust of the gases to and 15 from the explosion cylinders.

Another object of this invention is the production of a simple and efficient combustion engine consisting of a minimum number of parts which will be very inexpensive 20 to install and maintain.

With these and other objects in view, this invention consists of certain novel combinations, constructions, and arrangements 25 of parts as will be hereinafter fully described and claimed.

In the accompanying drawings:—

Figure 1 is a central longitudinal section through one of the cylinders.

Fig. 2 is a top plan view of the base for 30 supporting the explosion cylinders.

Fig. 3 is a central transverse sectional view through the cylinders.

Fig. 4 is a central transverse section taken 35 through the piston rod.

Fig. 5 is a central longitudinal section through one of the pistons.

Fig. 6 is a vertical section through a portion 40 of one of the cylinders, showing the manner in which the gases are admitted or conveyed to the explosion cylinders.

Fig. 7 is an enlarged vertical section through the lower end of one of the valve stem supporting shoes.

Fig. 8 is a detailed perspective of one 45 of the cam supporting rods.

Referring to the accompanying drawings by numerals it will be seen that 1 designates the base of the device which supports the explosion cylinders 2 and this base 1 is provided with projecting portions 3 for supporting the crank shaft 4. This crank shaft 4 carries a fly-wheel 5 and is journaled upon the journal portion 6 of the bracket portions 3. A piston rod 7 is connected to the crank 50 shaft 4 and this crank shaft 4 also carries a sprocket wheel 8 over which a chain 9

passes, the chain in turn passing over the sprocket wheel 10 carried by the auxiliary driving shaft 11.

The auxiliary driving shaft 11 carries a 60 pair of beveled gears 12, which beveled gears 12 mesh with the beveled gears 13 carried by the cam-supporting rods 14. One of these rods 14 extends along each side of the base 1 as illustrated in Fig. 2 of the drawings. 65

These cam-supporting rods 14 carry valve actuating cams 15 which cams 15 are arranged in pairs adjacent the respective ends of the rods 14. The cams 15 are adapted to engage the spring-pressed jaws 16 carried by 70 the valve stems 17. The valve stems 17 work through the depending portions 18 of the cylinder heads 19 and a coiled spring 20 is mounted upon each depending portion 18 for normally urging a downward pressure 75 upon the flange portion 21 of the jaw 16, the jaw being secured to the stem 17 by means of a pin 22. The jaw 16 is provided with a reduced neck 23, which neck is slidably mounted in the socket 24 of the depending portion 18 of the cylinder head 19 so as to have a free upward and downward movement for actuating the valves 25 carried by the valve stems 17. 80

It should be understood that the valves 85 25 are preferably arranged in pairs within the cylinder heads 19 and the cams 15 of each pair are arranged so as to alternately open and close the respective valves 25 carried by the cylinder heads 19. 90

Each cylinder head 19 is provided with the usual water jacket 26 and carries a spark plug 27 which is connected in any suitable or desired manner to a source of electrical supply and igniting mechanism for igniting 95 the charge within the cylinder 28. The cylinder 28 is also provided with a water jacket 29 having a discharge aperture 30 for connecting the siphon whereby the supply of water in the water jackets 26 and 29 100 may be controlled.

A double-ended piston 31 is slidably mounted within the cylinder 28 and this double-ended piston 31 is provided with a central brace 32 to which is connected the 105 spool 33 and the piston rod 7 is connected to the spool 33 for the purpose of reciprocating the double-ended piston 31 within the cylinder 28. The spool 33 is adapted to travel in a longitudinally extending slot 34 110 formed in the side of the cylinder 28 as clearly illustrated in Fig. 5 of the drawings.

As illustrated clearly in Fig. 3, the piston rod 7 works between the cylinders 28, which cylinders 28 are arranged so as to extend in parallel relation with respect to each other. The spools 33 are supported upon a connecting rod 35, which connecting rod is secured to the opposite pistons working in the oppositely disposed cylinders 28.

It should be understood that a cylinder head 19 is carried by each end of the cylinder 28 and these heads are constructed similarly to each other and are provided with inlet and exhaust valves of the same construction as that previously described, which valves are actuated by one pair of the cams 15 carried by the rods 14.

An inlet pipe 36 is connected to the channel 37 formed in the outer casing of the cylinder 28 and this channel 37 communicates with the passageways 38 formed in the cylinder 28, which passageways 38 communicate with the inlet ports 39. The inlet port 39 is controlled by means of the valve 25, actuated as above described.

Each cylinder head 19 is provided with an exhaust port 40, controlled by one of the valves 25.

The base 1 is provided with a cradle 1^a into which is seated the depending base 2^a of the cylinders 28.

From the foregoing description it will be seen that a very simple and efficient valve actuating means has been produced for controlling the opening and closing of the valves for permitting the inlet gases and exhaust gases to be readily admitted to or discharged from the explosive cylinder, the explosion of the device taking place at al-

ternate times at the opposite ends of the cylinder 28.

What I claim is:

1. An engine of the class described comprising a base, a plurality of explosion cylinders arranged in parallel relation, a piston working in each cylinder, each piston comprising a pair of piston heads, a plurality of converging arms connecting the respective heads of each piston, said arms provided with a socket near the junction thereof, a spool seated within said socket and fixedly secured thereto, a crank pin inserted through said spool and through the junctions of said arms, said spool constituting a bearing for said crank pin, each cylinder provided with a longitudinally extending elongated slot, said slot constituting a guide for said spool for permitting the reciprocation of said pistons within said cylinder, and a crank arm for operating said crank pin.

2. An engine of the class described comprising a base, a plurality of explosion cylinders arranged in parallel relation, a piston working in each cylinder, each piston comprising a pair of piston heads, arms connecting the respective heads of each piston, a spool carried by said arms, a crank pin passing through said spool, said spool constituting a bearing for said crank pin, each cylinder provided with a longitudinally extending slot, said slot constituting a guide for said spool and permitting the reciprocation of said pistons within said cylinder and means for operating said crank pin.

In testimony whereof I hereunto affix my signature.

RICHARD M. DAY.
